SETH A. CRONE, OF EAST ORANGE, NEW JERSEY.

BRAKE-BEAM FOR RAILWAY-CARS.

1,076,956.

Specification of Letters Patent.

Patented Oct. 28, 1913.

Application filed April 8, 1912, Serial No. 689,199. Renewed July 16, 1913. Serial No. 779,391.

To all whom it may concern:

Be it known that I, SETH A. CRONE, a citizen of the United States, and a resident of East Orange, in the county of Essex and State of New Jersey, have invented certain new and useful Improvements in Brake-Beams for Railway-Cars, of which the following is a specification.

The invention relates to improvements in brakes for railway cars and the like, and it consists in the novel features and structure hereinafter described, and particularly pointed out in the claims.

The invention pertains more particularly to brake-heads adapted to carry the brake-shoes and to the special means I provide for adjustably securing said heads on grooved sleeves present on the ends of brake-beams.

The main object of the present invention is to provide a very durable brake-head lacking complexity and capable of being adjustably secured to the beam by very durable and inexpensive means adapted to the groove in the sleeve on which the brake-head is mounted.

The invention will be fully understood from the detailed description hereinafter presented, reference being had to the accompanying drawings, in which:

Figure 1 is a side elevation of a portion of one end of a brake-beam having thereon a grooved sleeve, brake-head and securing means embodying my invention; Fig. 2 is a central vertical section through the same on the dotted line 2—2 of Fig. 1; Fig. 3 is a top view of the same, and Fig. 4 is a face view, Fig. 5 an edge view and Fig. 6 a top view of a key employed in accordance with my invention for securing the brake-head upon the beam.

In the drawings, 10 designates the brake-head as a whole, and this head with the exception of the features embracing my invention may be of customary or any suitable form and construction. The brake-beam is numbered 11 and the sleeve thereon 12, said sleeve being formed with a circumferential groove 14 extending around or partly around the same, as usual, and receiving the head 10 in a manner well understood.

The brake-head 10 is formed with an integral back portion 15 and has at the upper end of said portion a transverse entrance slot 16 and at the lower end of said portion a transverse exit slot 17 for a key or strip

18 whose middle portion enters the groove 14 and firmly bears against the sleeve 12 and effects the securing of the head on the beam. The key 18 will preferably be in the form of a flat strip of strong spring metal, as represented in Figs. 4, 5 and 6, and will have its upper end flanged outwardly, as at 19, the middle portion of the flange being less in width and greater in length than the body of the flange and creating a tongue 20. The back of the head 10 adjacent to the entrance slot 16 is formed with a vertical recess 21 which is about the width of and freely receives the tongue 20, as may be understood on reference to Fig. 1, and said head at the opposite sides of said recess 21 is formed with interior transverse recesses 22 adapted to receive the end portions of the flange 19 when the key 18 is in position locking the head 10 to the beam. The engagement of the ends of the flange 19 with the recesses 22 serves to lock the key 18 in position and to guard against any accidental displacement of the key. The entrance slot 16 is, however, of such proportion fore-and-aft that the upper end of the key 18 may be forced inwardly to free the flange 19 from the recesses 22 and permit of the removal of said key, when desired. The tongue 20 and flange 19 form a head for the key 18 and not only aid in the proper securing of the key in position but facilitate the application of the key to the head 10 and its removal therefrom.

The head 10 is an integral casting and lacks hinged-parts, adjusting bolts and nuts and the like, and in consequence is of very durable character and simple of construction. The key 18 is an integral strip of spring metal and when in position bears at its ends against the walls of the entrance and exit slots or openings 16, 17, respectively, and at its middle portion lies within the groove of the sleeve 12 and bears strongly against the rear side of said sleeve, with the result that the head is bound very firmly against the sleeve and efficiently secured thereto. In securing the head on the sleeve, the key or strip 18 is applied to the entrance opening 16 and then forced or driven downwardly until the lower end thereof takes its bearing against the wall of the lower opening 17. The flange 19 is, finally, caused to engage the recesses 22 for the purpose of releasably spring-latching or locking the key or strip 18 to the head and

against accidental displacement. The entrance and exit slots or openings 16, 17 may be substantially one below the other but are inwardly of the vertical plane of the rear or back surface of the groove 14 of the sleeve 12, so that when the normally flat key or spring strip 18 is driven downwardly through the inlet opening 16 it will become flexed against said sleeve on the passage of its lower portion to the exit slot or opening 17, as shown in Fig. 2.

The slot 17 is shown as open at its lower end with the key or strip 18 protruding therethrough, and this is the preferred construction for several reasons, but the main essential is that the lower end of the key or strip 18 have a substantial bearing against the head regardless of the exposure of its extremity.

20 I do not confine my invention to details of construction further than may be rendered necessary by my claims, the essential consideration being that the independent strip or key 18 when driven home shall firmly bear at its upper and lower ends against the head and at an intermediate portion against the part to which the head is to be secured,—this part preferably being a sleeve on the end of the beam on which the tubular 25 part of the head is fitted and which has a groove or reduced portion to receive such intermediate part of the key or strip.

What I claim as my invention and desire to secure by Letters Patent, is:

35 1. In a brake-beam, the combination with an adjustable brake-head having an integral closed back portion, a part of the beam on which said head is mounted, and a flexible spring key for securing said head on said 40 part, said back portion of the head having upper and lower openings for said key inwardly from the vertical plane of the rear or back surface of said part of the beam on which the head is mounted, and said key 45 being normally substantially straight so as to become flexed against said part when driven through the upper to the lower of said openings.

2. In a brake-beam, the combination with 50 an adjustable brake-head having an integral closed back portion, a part of the beam on which said head is mounted, a flexible spring key for securing said head on said part, and means for detachably securing one end of 55 said spring key, said back portion of the head having upper and lower openings for said key inwardly from the vertical plane of the rear or back surface of said part of the beam on which the head is mounted, and 60 said key being normally substantially straight so as to become flexed against said part when driven through the upper to the lower of said openings.

3. In a brake-beam, the combination with 65 an adjustable brake-head having an integral

closed back portion, a grooved sleeve on the end of the beam on which said head is mounted, and a flexible spring key for securing said head on said sleeve and entering the groove therein, said back portion of the 70 head having upper and lower openings for said key inwardly from the vertical plane of the rear or back surface of the groove in said sleeve, and said key being normally substantially straight so as to become flexed 75 against said surface of said groove when driven through the upper to the lower of said openings.

4. In a brake-beam, the combination with an adjustable brake-head having an integral 80 closed back portion, a grooved sleeve on the end of the beam on which said head is mounted, a flexible spring key for securing said head on said sleeve and entering the groove therein, and means for detachably securing one end of said spring key, said back portion of the head having upper and lower 85 openings for said key inwardly from the vertical plane of the rear or back surface of the groove in said sleeve, and said key being 90 normally substantially straight so as to become flexed against said surface of said groove when driven through the upper to the lower of said openings.

5. In a brake-beam, the combination with 95 an adjustable brake-head, a part of the beam on which said head is mounted, and an independent flexed spring key bearing at its ends against the head and at an intermediate portion against said part, said head 100 and one end of said key respectively having an interengaging recess and a flange releasably latching the key to the head.

6. In a brake-beam, the combination with an adjustable brake-head, a grooved sleeve 105 on the end of the beam and on which said head is mounted, and an independent key bearing at its ends against the head and at an intermediate portion against said sleeve within the groove thereof, said head and one 110 end of said key respectively having an interengaging recess and a flange releasably latching the key to the head.

7. In a brake-beam, the combination with a brake-head having at upper and lower 115 sides of its back open transverse slots, a part of the beam on which said head is mounted, and an independent key in said slots and bearing at its ends against the outer walls thereof and at an intermediate 120 portion against said part.

8. In a brake-beam, the combination with a brake-head having at upper and lower sides of its back open transverse slots, a part of the beam on which said head is 125 mounted, and an independent spring key in said slots and bearing at its ends against the outer walls thereof and at an intermediate portion against said part, said key at its upper end being releasably latched to 130

said head and having a laterally projecting portion to aid in its removal.

9. In a brake-beam, the combination with a brake-head comprising a tubular portion having at upper and lower sides of its back open transverse slots, a grooved sleeve on the end of the beam and on which said head at its tubular portion is mounted, and an independent spring key in said slots and bearing at its ends against said head and at an intermediate portion against said sleeve

within the groove thereof, said key at its upper end being releasably latched to said head and having a laterally projecting portion to aid in its removal. 15

Signed at New York city, in the county of New York and State of New York, this 6th day of April A. D. 1912.

SETH A. CRONE.
